UNITED STATES PATENT OFFICE.

ALLISON W. AUGUR, OF CHICAGO, ILLINOIS.

INTERNAL-COMBUSTION ENGINE.

1,119,386.

Specification of Letters Patent.

Patented Dec. 1, 1914.

Application filed July 29, 1912. Serial No. 711,992.

To all whom it may concern:

Be it known that I, ALLISON W. AUGUR, a citizen of the United States, residing at Chicago, in the county of Cook and State 5 of Illinois, have invented certain new and useful Improvements in Internal-Combustion Engines, of which the following is a specification.

My invention relates to improvements in 10 internal combustion engines and has for its general object to provide a two-cycle engine in which the cylinders are positively scavenged and in which the fuel charges are introduced under pressure following the 15 introduction of a non-combustible scavenging blast, so that the fresh fuel charge may not encounter the hot gases of the previous spent charge, and that thereby danger of back-firing may be obviated.

20 My invention has among its objects to provide a structure of this general character which is simple in construction, positive in its scavenging and charging operations, and efficient in power production.

25 In the drawings wherein I have illustrated the embodiment of my invention:—Figure 1 is a longitudinal vertical section through a two-cylinder engine embodying my invention, with parts broken away; Fig. 30 2 is a vertical section on line 2—2 of Fig. 1; Fig. 3 is a plan view of the engine; Fig. 4 is a horizontal section on line 4—4 of Fig. 1; Fig. 5 is a fragmentary section on line 5—5 of Fig. 3; Fig. 6 is a section on line 6—6 of Fig. 5; Fig. 7 is a section on line 7—7 of Fig. 6; and Figs. 8 and 9 are side and end elevations respectively of a valve-timing cam.

35 The engine units—*i. e.*, cylinders, pistons and associated parts—are arranged in pairs, each unit having two cylinders and a compound piston for the provision of a power element and a pump element in the same physical structure, the pump element of 45 each unit being connected with the power element of the companion unit through suitably controlled passage ways to act as an air pump for the supply of scavenging air to the companion unit.

50 In the construction shown 10 and 10' indicate in general the two engine units the frames of which are preferably cast *en bloc* to afford for the respective, appropriately-separated, units the combustion cylinders 55 11—11' and pump cylinders 12—12'. The cylinder structures of the respective units

receive the respective piston structures 13 and 13' each having portions of two diameters, as shown respectively 14, 15, and 14' 60 15' to coöperate with the corresponding cylinder portions, thus obviously providing for each unit a power member and a pump member in tandem. The piston structures 13—13' are of course connected by respective piston rods 16—16' with the cranks 65 17—17' of a crank shaft 18 mounted in suitable bearings in a base structure or crank casing 19 secured to the cylinder casting, the cranks of the pair being preferably directly opposed so that the piston structure 70 of one unit makes its instroke as the other makes its out-stroke.

Each of the combustion cylinders 11, 11', is water jacketed, for cooling in the conventional fashion, the walls 21 and 21' 75 forming the water jacket space for the upper combustion cylinders merging into the cylinder walls 12, 12' of the pump members. Between the exterior walls of the two cylinder units I provide vertical walls 22—22' 80 and 23, top wall 24 and bottom wall 25 to provide two vertical air chambers 26 and 26', respectively, communicating through ports 27 and 27' with the upper ends of the pump elements of units 10 and 10', and also 85 respectively communicating by ports 28—28' with ducts 29' and 29 leading through the heads of the respective units to the power cylinders 11'—11 thereof, thus providing from the pump cylinder of each unit to the 90 power cylinder of the other unit, an air passage enlarged, in part, to form an air compression chamber. For the introduction of air into the respective compression chambers 26—26' I provide ports in the bottom wall 25 of the chamber structure controlled by inwardly opening check valves 95 30—30' and I also preferably provide in cylinders 12, 12', intake ports 31—31' positioned to be passed by the respective pistons 100 at the ends of their out-strokes. The intake duct 29 has communication with the cylinder 11 controlled by a valve 33 inwardly opening against the resistance of a light spring 34 acting against an adjustable head 35 or the valve stem 36, the spring being incased in a housing 37 threaded into the head of the engine. The spring is suitably tensioned merely to hold the valve normally closed and to respond to a predetermined difference in pressure as between the sides of the valve. By adjust-

ment of the head 35, which acts as the limitation stop to limit the throw of the valve, the valve opening may be regulated to suit the duration of opening of the exhaust ports. Similar provision is of course made for the cylinder 11', the parts being indicated by similar numerals distinguished by the exponent prime ('). The cylinders 11-11' have their open exhaust ports 38-38' positioned to be uncovered at the end of the out-stroke of the power piston, as is common in two-cycle construction.

From the foregoing it will be apparent that the pump member 12-15 of unit 10, on its out-stroke from the position shown in Fig. 1, will cause air to be drawn through the valve 30 into chamber 26 (such air introduction being supplemented by the air entering through port 31 at the end of the piston out-stroke) and that on its instroke, which terminates with the parts in position shown in Fig. 1, it will force the air through the path 26-28' 29' and valve 33' of the companion unit into the cylinder 11' whence said air finds escape through the exhaust ports 38'. Obviously too, the pump element of the opposing unit may act in the same way with respect to cylinder 11. By this arrangement I provide in a two-cycle engine appropriate means automatically to scavenge the engine during the period of time that the exhaust ports are open, by positively forcing through the power cylinder fresh air impelled by the pump element of a companion engine unit.

The air pump cylinder capacity for each unit is materially greater than the capacity of the power cylinder, and the in-take valve is so set that there is a flow of air (or mixture, as hereafter described) through the power cylinder as long as the exhaust ports are open.

The fuel,—i. e., the gasoline or other hydrocarbon,—is forced under pressure into position for admixture with an air body which is also under pressure, and the mixture, controlled by suitable valve means, is introduced into main air body flowing into the cylinder to be charged at an appropriate time in the engine cycle. Specifically 40 indicates a fuel-holding pressure tank into which fuel is forced through a pipe 41 from a pump 42 operated by connection 43 with an eccentric 44 on crank shaft 18, said pump receiving fuel from the pipe 45 leading to a reservoir not shown. A return pipe 47 leads from near the bottom of the tank 40 through a pressure controlling check valve 48 and a connecting pipe 49 back to the reservoir, the valve 48 being of any suitable character to oppose a definite resistance to the return of the fuel to the reservoir. The top of the tank 40 is closed (though it may have a valved connection 50 to a source of constant air pressure supply to enable the

functions of the device to be performed in starting the engine, or if the pump 42 for any reason fails, or its connection become disturbed) and the imprisoned air tends constantly to expel the fuel. The construction described is such that the pump, working constantly while the engine is in operation forces fuel into tank 40 raising its level and imprisoning air in the upper portion of the tank until such time as the air pressure 75 on the fuel may unseat the valve 48 and return fuel to the reservoir by the return pipe 47, 49, after which the air pressure is kept nearly constant by the relief of valve 48, thus insuring that all times during the 80 working of the apparatus the fuel will be maintained under a definite pressure limited by the adjustment of valve 48. From the bottom of the tank 40 run the two fuel pipes 52-52' for connection with appliances of 85 the two respective units to control the admission of fuel to their combustion chambers. These appliances being duplicates I will describe only those connected with the unit 10, it being understood that like parts 90 provided in the duplicate apparatus are designated by like reference numerals distinguished by the exponent prime ('). Pipe 52, as best shown in Figs. 6 and 7, leads to a port 54 controlled by a needle valve 55, said port opening through the seat 56 for a valve 57 which controls the fuel flow and also the communication between two chambers 58 and 59 in a suitable fitting 60. Chamber 58 has communication 100 through a pipe 61 with an air chamber 62 suitably mounted on the engine frame and having valved controlled communication through a tube 63 and ports 64 with the compressed air chamber 26', such passage 105 being normally closed by a valve 65 inwardly opening into chamber 62 and normally retained on its seat by a spring 66. In this specific construction I prefer to make the tubular member 63 in the form of 110 a connecting thimble supporting chamber 62 on the top of the engine frame and constituting also a valve-cage in cooperation with the spring 66 surrounding the stem and bearing on the bottom of the cage. 115

The mixing chamber 59 below valve 57 has pipe connection 67 with a nozzle 67' opening into the air passage 29 in the direction of air flow through said passage. The valve 57 which controls the mixing and 120 charging operations is preferably mechanically operated from the engine shaft and to this end receive from above the pressure of a stiff spring 69 located in a housing 70 screwed into fitting 60, said valve having a 125 stem 71 extending downward through suitable bearing into the crank casing of the engine and there provided with a roller 72 to bear on a cam structure mounted on the engine shaft. A single cam sleeve 73 may 130

be provided for operating both valve rods 71 and 71', and for timing adjustment the cam sleeve 73 is made slidable on the shaft upon a key 74, sliding movement being imparted thereto by a shipper lever 75 pivoted as at 75^a and having its motion receiving end extending into the space between the top of the crank case and the bottom wall 25 of the compressed air chambers 5. The sleeve 73 is preferably cylindrical except where on diametrical sides it is provided with two cam projections 76—76' each of which has its rear edge, with reference to the direction of rotation of the shaft, on a straight line for uniform timing of the closure of the valve and its forward edge running at an angle to the rear edge so that farther the sleeve is shifted to the right (Fig. 1 or Fig. 7) the earlier the valve will 10 open and the longer it will be held open, so that, as will be apparent, the fuel content of the charge may be varied to suit changes of running conditions.

It will be understood that my engine will 25 be provided with ordinary means for ignition of fuel charges, oiling, and like operations, but I have not illustrated such matters as the present invention is not concerned therewith and the same are well understood 20 by all persons versed in this art.

The running of my engine causes the operation of pump 42 which forces fuel as hereinbefore described into the pressure tank 40 until it is under such pressure that the resistance of valve 48 may be overcome and surplus fuel returned to the reservoir. The pressure thus engendered is higher than any air pressure which will exist in the auxiliary air chamber 62 and therefore when valve 57 45 is open fuel is forced through pipe 52 past the needle valve 55, and sprayed into the mouth of eduction chamber 59, the same operation of course taking place for each cylinder. Assuming that the engine is running 50 with the parts in the position as shown in Fig. 1 explosion of the compressed charge in cylinder 11 drives the working piston on its out-stroke, the working pressure within the cylinder holding valve 33 closed. The pump 55 element 12'—15' of unit 10' therefore forces air under pressure through port 27' into the air chamber 26', and when the pressure becomes high enough it forces open valve 65 and fills the supplemental air chamber 62 60 with compressed air. When the power piston of unit 10 reaches the end of its out-stroke it opens the exhaust ports 38, instantly reducing the pressure in the cylinder, whereupon valve 33 is opened by preponderance of pressure in the air chamber 26' and compressed air sweeps through the cylinder driving out the spent gases. This positive scavenging, which commences automatically instantly upon the opening of 65 the exhaust port, insures that a body of

fresh air, substantially free from combustible material, is introduced into the combustion chamber between the time that the exhaust ports open and the time that a fresh fuel charge is introduced into the chamber. 70

As soon as the air from the main compression chamber 26' begins its flow through the combustion chamber 11, valve 65 between the main compression chamber and the supplemental air chamber will close, maintaining supplemental air chamber 62 under relatively high pressure until such time as its pressure is utilized in conveyance of the fuel into the moving air body in intake passage 29. While the exhaust ports of the combustion chamber are open, but at a time depending on the adjustment of the cam member 73, valve 57 is opened by the operation of cam 76 on valve rod 71, thus opening the fuel supply port 54 and the outlet from the 80

supplemental air chamber 62 so that fuel is expelled in a more or less atomized state into the mixing chamber 59, and is carried by the air flowing from supplemental chamber 62 through the pipe 67 and nozzle 67' into 90 the main air body with which it flows through passage 29 and into the combustion chamber 11 through the open valve 33. At a moment predetermined by the construction of the cam 76,—and which I prefer should be 95

substantially coincident with the moment of closure of the exhaust port for the combustion chamber,—the controlling valve 57 is again seated, shutting off the fuel supply and closing the outlet of supplemental air 100 chamber 62. The valve 33 is then seated as soon as the pressure within the cylinder substantially equals the pressure in air chamber 26' and as the piston continues on its in-stroke it compresses the new charge. It will 105

be observed that any tendency to stratification of the mixture results in the location of the richest mixture at the highest elevation in the cylinders so that rapid response to ignition is insured. Furthermore the inter-position of an appreciable body of air substantially free from combustible material between the fresh fuel charge and the previously spent charge insures that the fresh 110 charge will not be ignited from the previous charge and so back firing is obviated. The shape of the walls of the clearance space in the head of the combustion chamber is de-signed to promote efficiency in scavenging

and the tendency to stratification of the mixture, the interior surface of the head throughout a portion 100 centering at the valve 33 preferably following substantially a parabolic curve larger in its extreme circumference than the circumference of the 115 cylindrical surface in which the piston trav-els, and connected with the cylindrical por-tion by a curved deflecting shoulder 101 which meets the truly cylindrical wall at

nearly right angles, so that the gases spread 120

5 by the valve 33 and tending to follow the parabolic wall, may be deflected inwardly by the shoulder 101 to eddy toward the center of the cylinder head. Thus the tendency of the inflowing gases' body will be to fill the head before the incoming gases move downward through the cylindrical portion of the combustion chamber.

10 It will be observed that although the cylinder is always charged to its full capacity with a fresh charge, the fuel content of the charge is variable as a result of variations in the setting of valve-controlling cam member 73, so that the richness of the mixture 15 may easily be accommodated to varying running conditions without sacrifice of the positive character of the construction.

20 While I have herein described in some detail a particular embodiment of my invention it will be apparent to those skilled in the art that numerous changes might be made in the details of construction thereof without departure from the spirit of my invention and within the scope of the appended 25 claims.

What I claim is:

1. In a two-cycle engine, the combination of the cylinders, each having a check valved 30 inlet port and an open exhaust port, each said cylinder having a compressed air chamber opening to said valve port, means for supplying air under pressure to each of 35 said chambers, said means associated with opposite cylinders, a mixing chamber for each cylinder, means for supplying fuel thereto, means for supplying air under pressure to the mixing chambers, and valved 40 means for each cylinder controlling the admission of fuel and air to the mixing chambers for communication with the respective valved inlets.

2. A two-cycle engine, comprising two 45 units, each unit having a power element and a pump element, a structure connecting the cylinders of said units providing two compression chambers, each having an opening to the pump cylinder of one unit and to the power cylinder of the other unit, inwardly opening check-valves controlling the communication of the respective power cylinders 50 with said air passages, fuel supply ducts leading to said passages, supplemental air chambers each having communication with the fuel supply duct and the compression 55 chamber for one of said units, valves controlling the connection of said supplemental air chambers with the said compression chambers, valves controlling the connection 60 of said supplemental chambers with the respective fuel supply ducts, and means timed by the operation of the engine for operating the last said valves.

65 3. In a two-cycle engine, a working element and a pump element operating oppositely, a fuel pump driven by said engine, a

fuel reservoir containing air maintained under pressure by said fuel pump, a duct connecting said reservoir to the working cylinder and having a mixing chamber, an air passage for said air pump to said working 70 cylinder including a compression chamber within which air is compressed by one of said oppositely operating parts, valved means for effecting communication between said compression chamber and the mixing 75 chamber of the fuel duct, a valve controlling the introduction of mixture from said mixing chamber, and variable timing means operated by the engine for controlling said valve.

4. In an engine, the combination of a cylinder, a piston therein, said cylinder having an inlet opening in its head and an outlet opening in its side wall opened by the retracted piston, a pumping instrumentality 85 having a reciprocable part operable coincidentally with operations of the piston to compress air for a scavenging passage through the cylinder from its head toward its piston when said piston is fully retracted, 90 and means for supplying fuel to said compressed air a predetermined time after the opening of said outlet by the retracted piston, for supply of carbureted air to said scavenged cylinder.

5. In an engine, the combination of a cylinder, a piston therein, said cylinder having an inlet opening in its head and an outlet opening in its side wall opened by the retracted piston, a pumping instrumentality 100 having a reciprocable part operable coincidentally with operations of the piston to compress air for a scavenging passage through the cylinder from its head toward its piston when said piston is fully retracted, fuel-supply means opening into said inlet, storage means associated with said fuel-supply means and communicating with the pumping instrumentality for potentiation before the opening of said outlet by the 105 fully retracted piston, and means, operable a predetermined time after said opening of the outlet by the piston, for operating said fuel-supply means.

6. In a two-cycle engine comprising the 115 usual cylinder and piston, the combination of means for supplying compressed air to the cylinder, for scavenging as the piston approaches the end of its working stroke, and means for injecting fuel, associated with 120 compressed air into the path of the scavenging air before entry into the cylinder and at a predetermined time, while the passage to the cylinder is open.

7. In a two-cycle engine comprising the 125 usual cylinder and piston, the combination of an inwardly opening check valve in the cylinder, means for supplying compressed air, through the said valve to the cylinder for scavenging as the piston approaches the 130

end of its working stroke, and means for injecting fuel, associated with compressed air into the path of the scavenging air before entry into the cylinder and before the closure of said check valve on the instroke of the piston.

In testimony whereof I hereunto set my hand in the presence of two witnesses.

ALLISON W. AUGUR.

In the presence of—

MARY F. ALLEN,
W. LINN ALLEN.
